UNITED STATES PATENT OFFICE.

HAROLD D. PEOPLES AND GEORGE W. BIDYKOFFER, OF SOMERDALE, OHIO.

ADJUSTING MECHANISM FOR PROPELLER-BLADES.

1,329,473.

Specification of Letters Patent. Patented Feb. 3, 1920.

Application filed November 30, 1917. Serial No. 204,798.

To all whom it may concern:

Be it known that we, HAROLD D. PEOPLES and GEORGE W. BIDYKOFFER, citizens of the United States, residing at Somerdale, in the county of Tuscarawas and the State of Ohio, have invented new and useful Improvements in Adjusting Mechanism for Propeller-Blades, of which the following is a specification.

10 The present invention relates to propellers, and more particularly to means for adjusting the blades of the propellers to increase or reverse the resistance of the same to the fluid medium in which the propeller is operated.

15 The object of the present invention is to provide an adjusting device, of this character which is relatively simple in construction, light in weight, and compact for 20 application to air craft and the like where such characteristics are required; to provide a device which is operable on all of the blades of the propeller simultaneously; and to provide a device which may be adjusted or 25 operated during the rotation of the propeller and without disconnecting the same from the source of power, the device being constructed to gradually change the positions of the blades to prevent undue shock and strain 30 upon the mechanism transmitting power to the propeller.

The above, and various other objects and advantages of this invention will be in part described, and in part understood, from the 35 following detailed description of the present preferred embodiment, the same being illustrated in the accompanying drawings, wherein:

Figure 1 is a longitudinal section through 40 a propeller blade adjusting device constructed according to present invention.

Fig. 2 is a transverse section taken through the propeller in the medial plane thereof, the blades being broken away.

45 Fig. 3 is a detail perspective view of the shifting means employed.

Fig. 4 is a detail perspective view of the hub or block upon which the blades are mounted, and to which the adjusting device 50 is applied.

Referring to these drawings, 10 designates a driven shaft adapted to be connected to a motor in any suitable manner, and upon the outer end of which is mounted a hub or block 11 of substantially circular contour. The hub 11 is provided with radial openings

12 which extend from a point spaced from the central axis of the hub through the peripheral surface thereof, and which may be of any desired number to correspond with 60 the number of propeller blades employed.

The hub 11 carries a plurality of propellers 13, the same being provided upon their inner ends with journals 14. The journals 14 are seated at their outer ends in recesses 65 formed in the stems or inner ends of the blades 13, and are held therein by rivets 15 secured transversely through the blades 13 and the journals 14. The inner ends of the blades 13 are seated against the peripheral surface of the hub 11, and the latter is preferably flattened at such points to provide bearing surfaces 16 for supporting the blades. These surfaces 16 are formed about 70 the radial openings 12, and the inner ends of the journals 14 project into the radial openings and provide rotatable supports for 75 the blades 13.

The block or hub 11 is provided with a circular concentric row of transverse slots 80 or apertures 17 arranged to intersect the radial openings 12 near the axis of the hub, and which are preferably offset slightly longitudinally from the axis of the openings 12 for a purpose which will hereinafter 85 appear. The journals 14 have each a pinion 18 fixed thereto intermediate its ends and adapted to lie within the adjacent slot 17. The slots 17 are offset as above described to provide guideways in one end of each slot 90 between the adjacent pinion and the end wall of the slot for the reception of rack bars 19. The rack bars correspond in number to that of the slots 17 and are held in meshing relation to the pinions 18 at all times. 95

The rack bars 19 are pivotally mounted upon a carrier disk 20 slidable mounted upon the shaft 10 and movable toward and from the hub 11. Each rack bar 19 has at its inner end adjacent the disk 20 a pair of laterally extending spaced apart lugs 21 receiving therebetween an ear 22 projecting from the disk 20. A bolt 23 pivotally connects the ear between the lugs to hinge the rack bar to the disk. The inner ends of the rack bars 100 19 are flat and adapted to engage against the flat surface of the disk 20 to hold the rack bars from undue vibration on the disk. The rack bars 19 are arranged upon the disk to engage the teeth of the rack bars with 105 the pinions 18 when the rack bars are inserted through the slots 17.

The disk 20 has a peripheral annular groove in which is seated a split ring 24, the sections of which have outturned flanges 25 at the meeting ends of the sections, and which are held together by bolts 26. A link 27 has forked arms 28 at one end secured to the flanges 25 of the ring 24 and pivotally connected at 29 to an intermediate portion of a hand lever 30 fulcrumed at 31 to a suitable support or bracket 32. The ring 24 may be provided with a lubricator 33 mounted on the upper side of the ring and adapted to feed a lubricant to the groove of the disk 20 for reducing frictional contact between the ring and the disk, and admit the free rotation of the latter in the ring.

In operation, it is apparent that the shaft 10 may be rotated in the desired direction and at the desired speed to turn the hub 11 and its blades 13 together with the disk 20 which is connected to the hub by the rack bars 19. While this rotation takes place, the hand lever 30 may be moved in either direction upon its pivot 31 to shift the disk 20 by means of the relatively stationary split ring 24 and move the rack bars longitudinally through the slots or perforations 17. When the rack bars are shifted the pinions 18 are turned to rotate the journals 14 and turn the blades 13 about their longitudinal axes. The blades 13 may thus be adjusted to the desired angle with respect to the plane of the propeller for obtaining the desired resistance of the propeller, and for changing the direction of thrusts of the propeller, such changes being gradual according to the movement of the hand lever 30.

The device thus described is of such con-

struction, and the parts are so peculiarly combined that all of the parts may be made relatively strong, and relatively small to produce an assembled device which is compact, light in weight, and capable of withstanding the strains to which it may be subjected.

It is of course understood that various changes and modifications may be made in the details of construction and design of the above specifically described embodiment of the invention without departing from the spirit thereof, the changes and modifications being restricted only by the scope of the following claim.

What is claimed is:

In a propeller blade adjusting device, the combination of a shaft, a hub mounted on the shaft, blades carried by the hub and having journal portions keyed in the hub, pinions on said journal portions, racks extending slidably through the hub and engaging said pinions, a disk mounted upon said shaft for rotating therewith and for slidable movement along the shaft, ears projecting laterally from one face of the disk, laterally extending spaced ears formed upon said racks and extending outwardly from their toothed faces, the ears upon said rack engaging upon opposite sides of the corresponding ears upon said disk, means pivotally connecting the rack carried ears to the disk carried ears for pivotally connecting said racks to said disks, and means for shifting said disks longitudinally upon said shaft.

HAROLD D. PEOPLES.
GEORGE W. BIDYKOFFER.
